UNITED STATES PATENT OFFICE.

HARRISON A. SMITH, OF NEENAH, WISCONSIN, ASSIGNOR, BY MESNE ASSIGNMENTS, TO THE SERVIDOR COMPANY, OF NEW YORK, N. Y., A CORPORATION OF DELAWARE.

SERVICE CABINET.

Application filed May 23, 1921. Serial No. 471,566.

My invention relates to service cabinets for permitting transfer of articles to or from an enclosure, without at any time permitting free access to or from the enclosure by persons outside or inside the same.

The various objects of this invention are in the nature of improvements on and departures from the structure disclosed in United States Patent No. 1,222,964 to F. J. 10 Matchette, April 17th, 1917.

One object of the invention is to simplify the manipulation necessary in closing or opening either door. To simplify the closing operation, I have provided mechanism whereby the single movement of pushing the door into closed position, is all that is required of the operator, this movement automatically locking the door, adjusting the inter-locks, and the signals for indicating 15 the condition of the compartment. To simplify the opening operation I have provided for accomplishing that also by a single movement, in this instance the pressing of a push button which unlocks the door and permits spring mechanism to automatically 20 permit the door open.

Another object is to mount all the locking, inter-locking and signalling mechanism in a single casing, as a compact, unitary device.

Another object is to provide for the operation of the necessary signals and the mechanical inter-locking by a single reciprocating member. An advantage involved in 35 this is that the signals and the inter-lock may all be mounted in a single frame.

Another object is to materially simplify and reduce the amount of equipment necessary for manufacturing devices according to 40 my invention in different sizes. For this purpose, I have reorganized the parts so as to materially reduce the number of elements which need be altered in their dimensions, when the dimensions of the cabinet are 45 changed.

Another object is to provide a mechanism which can be readily operated at will, to release both the doors at once for cleaning the cabinet, or other purposes, but which nevertheless, provides just as complete protection 50 as if this feature were absent.

Another object is to eliminate the use of cylindrical members for parts of the mechanism subjected to load.

55 Further objects and advantages of my in-

vention will become apparent as the description proceeds.

In the accompanying drawings:

Figure 1 is an isometric view of a portion of a door in which a service cabinet according 60 to my invention has been embodied.

Figure 2 is an enlarged isometric view of one end of the locking and inter-locking mechanism, showing the hook carried by the door in position to enter the lock.

Figure 3 is an elevation of the entire locking and inter-locking mechanism, from the open side of the casing, which side is normally laid against the framework of the cabinet;

Figure 4 is a similar elevation with the inter-locking slides and movable signals removed; and

Figure 5 is a section on line 5—5 of Figure 3.

In the embodiment of my invention selected for illustration, each of the compartment doors carries a plate 12, provided with a hook 14, for engagement with the locking mechanism supplied, and a suitable handle element 16, serving merely as a grip for the operator in moving the door. One edge of each plate is substantially flush with the free edge of the door, and is apertured as at 18, to overlie a registering aperture 20, in the end piece 22 of casing 24. Through these apertures the signals for indicating the condition of the compartment are displayed.

The casing 24 is formed of a single piece 90 of sheet metal comprising a back portion 26, duplicate end portions 22, bent at right angles to back portion 26, and duplicate top and bottom walls 28 co-operating with the other walls to define a box-like enclosure 95 open at one side only. Suitable lugs 30 integral with the top and bottom walls 28, and bent to lie in a plane parallel to the back portion 26, provide for fastening the casing against the inner wall of the structure of 100 the compartment, so that when put in place, the casing completely houses the mechanism mounted therein.

Duplicate sets of locking mechanisms, arranged to co-operate with hooks for the same, are provided in opposite ends of the casing. These locking mechanisms comprise ejectors 32 and catches 34. Each ejector 105 comprises a flat body portion having sliding engagement with the rear wall 26 of the 110

casing, and is guided for limited sliding movement by a rivet 36, passing through the ejector and riveted into the rear wall 26, the ejector having a slot 38, the length of which slot limits the movement of the ejector. The body of the ejector is notched near its outer end to provide ample clearance for movement of catch 34, and at its extreme outer end carries an upwardly bent lug 40, flush with the upper portion of the hook receiving aperture 42 in the end of the casing. At its rear end the ejector carries lugs 44 and 46, lug 44 being arranged to co-operate with ejector spring 45 to throw the door open when the catch is withdrawn, and lug 46 co-operating with the inter-locking mechanism in a manner to be described hereinafter.

Catch 34 is another flat sheet metal member, slotted at 48 to receive rivet 50, which performs the same function as rivet 36. Catch spring 52 normally holds catch 34 in the position illustrated in Figure 4, and a manually actuated release lever 54 engages a shoulder in the body of the catch to move same downward, throwing the lug 56 out of the notch 58 in hook 14 to release the door. Lug 56 lies at a proper angle just back of aperture 42 so as to engage the sloping nose of hook 14 and be forced down until spring 52 engaging lug 53, snaps the catch up again, positioning lug 56 in notch 58. As the line of force of lever 54 in its action on catch 34 is not in alignment with slot 48, I prefer to provide an additional rivet 60, engaging the edge of catch 34 to prevent any tendency of the same to rotate.

Associated with the locking means at each end of the casing is a U-shaped supporting member, formed of sheet metal and comprising a relatively narrow bight 62, inter-connecting two parallel plates 64 lying in contact with the top and bottom walls 28 of casing 24.

This single sheet metal element embodies guiding and supporting means for all the movable parts associated with the inter-locking and signalling means, and receives one of the pintles of release lever 54. A pair of lugs 66, projecting from the inner edge of each plate 64, pass through registering apertures in the rear wall 26, and are riveted over as shown in Figure 5. The provision of these individual supports for the portion of the interlocking and signalling mechanism, associated with the locking means at the end of the casing, materially simplifies the process of manufacture and assembly.

Each release lever 54 comprises a single piece of sheet metal provided with projections 68 forming pintles entering the plate 62, and the rear wall 26 of the casing, a rearward projection 70 for co-operation with the inter-locking mechanism, and an actuating arm 72, bent downwardly and then

outwardly as indicated in Figures 4 and 5, and terminating in an eye 76. The actuating means engaging eye 76 for actuation of the release lever 54, is mounted in the element 78, forming part of the fixed structure 70 of the door 80, in which I prefer to install my service cabinet. It is the only portion of the entire operating mechanism not mounted in and supported by casing 24 and comprises a plunger 82, slideable through a face plate 84, fast on the element 78. A flange 86 engages plate 84 to limit outward movement of the plunger, and a push-rod 88 encircled by a compression spring 90, passes through eye 76. A shoulder 92 provides an abutment for one end of spring 90 which presses against eye 76 at the other end. If release lever 54 is free to be operated, plunger 82 may be pushed in to compress spring 90 and rotate the release lever against the opposing force of spring 52 to depress catch 34 and release hook 14. If, however, release lever 54 is locked against movement, plunger 82 can only operate to compress spring 90, without either unlocking the door, or injuring the transmission between the plunger and the locking element.

Slide 94 is the only element extending from one end of the casing to the other, and operates to perform the interlocking function and also the signalling function. This slide is supported and guided by apertured lugs 96, bent up from the remote edges of the bights 62 of the U-shaped supports for the sets of mechanism located at the ends of the casing. It slides in contact with the surface of each bight, and its reciprocatory movement is limited by projections 98 extending inwardly through slot 100, in each bight 62, and beyond the plane of bight 62 to selectively lock release levers 54 against actuation and compel opening the doors of the cabinet in alternate sequence. Suitable resilient means in the nature of a leaf spring 102 supported on a fixed pin 104, mounted on the rear wall 26 of the casing and engaging a movable pin 106 carried by slide 94, normally operates to hold slide 94 at one end of its path of movement.

In the position illustrated in the drawing the left-hand door is locked by the inter-lock, but the catch of the right-hand door may be manually released to obtain access to the cabinet. Upon reference to Figures 4 and 5 it will be noted that the left-hand projection 98 over-lies the arm 70, so that the left-hand release lever 54 cannot be actuated. At this time both ejectors 32 will be in the position indicated in dotted lines in Figure 4. The locking mechanism at each end of the casing is provided with a key 108 for automatically shifting the inter-lock slide 94 when the corresponding door is opened and closed again. Each key is pivotally supported on pintles entering plate 125 130

64 of the lock-support, and is normally resiliently urged toward the inclined position illustrated in the drawing by a leaf spring 110. At the end opposite spring 110 the key 5 has a portion 112 wide enough so that its edge is interposed in the path of lug 46 on the ejector, and a still wider portion 114, wide enough so that its edge will swing through a path lying partly in the plane of 10 slide 94 to encounter a lateral projection 116 on the slide and actuate the same. The right-hand door may now be opened by pushing in the corresponding plunger 82, and leaf spring 45 will throw the door partly 15 open by pushing ejector 32 against the end of hook 14. This movement will carry lug 46 past portion 112 of the key, rotating it into the position shown in dotted line in Figure 5, and passing beyond it to permit 20 it to return to the full line position. When the door is closed again the return movement of lug 46 will swing the key through an angle more than 90 degrees before the lug catch is clear of portion 112 and spring 25 110 will thereupon rotate the key through the rest of a displacement of 180 degrees, as indicated by the dotted line and arrow in Figure 5. During the first part of this movement, while the key is positively actuated by lug 46, portion 114 encounters projection 116 to shift slide 94 to its other position, in which the right-hand projection 98 over-lies the right-hand arm 70. The right-hand door, therefore, cannot be opened 30 until the opening and subsequent closing of the left-hand door has reset slide 94 in the position shown in the drawings.

For indicating to persons on both sides of the cabinet, the condition of the same, I 40 provide indicating means comprising two targets adjacent each side and means for changing the indications given by the targets each time one of the doors is operated. To make this part of the structure as simple as possible, I employ only one movable target adjacent each door, and position another fixed target where it may be covered by the movable target, or exposed by removing the same. The fixed targets 118 are light 45 strips of sheet metal suitably united as by spot welding at 120 to the end walls 22 of the casing. Each movable target comprises a plate 122, with its edge turned over as at 124 to form the indicating portion of the target, and lugs 126 engaging a vertical spindle 128, which spindle preferably extends from one plate 64 to the opposite plate. A small ear 130 is struck up from the edge of plate 122, to project through 50 an aperture 132, in the slide 94. It will be obvious that the reciprocatory movement of the slide will rotate the targets around their pivotal mountings, and as shown in Figure 5 the left-hand target has been swung to 55 cover the stationary target at that end, and

the right-hand target has been similarly swung, to move it out of alignment with aperture 20, and expose the stationary target.

The indicia employed will vary with the use to which the cabinet is put. In a cabinet employed for the transfer of goods from a delivery man or purveyor outside a house or other enclosure, to the customer within the enclosure, the cabinet will be empty after 70 the customer has opened his door and removed the contents. If the right-hand door, as shown in Figures 3, 4 and 5 is the receiving side, the movable target on the left and the fixed target on the right, are preferably 75 both lettered with the word "Empty". This will apprise the delivery man that the cabinet is in condition to receive an article in that particular compartment, and will also inform the customer that there is nothing 80 in that compartment for him to remove. Similarly the stationary target on the left and the movable target on the right, should carry indicia indicating that an article has 85 been deposited in the cabinet. This may be indicated by the word "Locked", or by any other suitable symbol.

It should be noted that slide 94 and casting 24 are the only two elements extending from side to side of the cabinet. In manufacturing cabinets of a large number of different thicknesses therefore, the only parts that need be changed are the casings and slides. It should also be borne in mind that 90 while I have illustrated my improved interlocking mechanism arranged to provide for operation of the doors in alternate sequence, the novel features thereof are equally applicable to arrangements providing for repeated operation of either or both doors, without 95 at any time permitting simultaneous operation of both.

After one door has been opened, the interlocking mechanism must be re-set to produce 100 subsequent opening of the other door. In the devices of the prior art this mechanism was practically inaccessible and it was therefore impossible for the user to succeed in opening both doors at once without taking 105 the device apart. In case milk or other fluids happened to be spilled inside the compartment, it was necessary therefore, to clean the interior of the compartment as thoroughly as possible from one side, and then 110 after closing the door on that side, to go to the other side and open the other door to complete the cleaning process. In the embodiment of my invention herein disclosed, after the right-hand door has been opened, 115 the parts may be reset to permit opening of the left-hand door without closing the right-hand door, by pushing ejector 32 in to the dotted line position with a screw driver or other tool and permitting it to snap back 120 into the full line position. The left-hand 125

door may now be opened from inside, leaving the compartment with both doors opened for cleaning or for any other purpose desired, as, for instance, when the customer desires to see and speak with the delivery man, but does not wish to leave the main door open.

Without further elaboration, the foregoing will so fully explain the gist of my invention, 10 that others may, by applying current knowledge, readily adapt the same for use under various conditions of service, without departing from certain features which may properly be said to constitute the essential 15 items of novelty involved, which items are intended to be defined and secured to me, by the following claims.

I claim:

1. In combination, a normally closed compartment, a plurality of doors providing access to said compartment, locking means operated by swinging said doors to closed position to hold them closed, manual means for releasing said locking means, said locking 25 means operating to throw the door open when released, and an inter-locking mechanism connecting said sets of locking mechanism to permit operation of said doors in predetermined sequence only.

2. In combination, a compartment, a plurality of doors associated therewith, locking means automatically operated by moving either door to closed position for holding said door closed, and interlocking means also 30 operated automatically by closing said door to prevent release of said door until another door has been opened and closed.

3. In combination, a compartment, a plurality of doors associated therewith, locking 40 means for each door, inter-locking means permitting operation of said locking means only in a predetermined sequence, a signal for indicating the condition of said interlocking means, and connections operated by movement of said door to closed position, for locking said door and actuating said interlocking means and signal.

4. In combination, a normally closed compartment, a plurality of doors providing access to said compartment, locking means operated by swinging said doors to closed position to hold them closed, manual means for releasing said locking means, said locking means operating to throw the door open 50 when released, and interlocking mechanism connecting said sets of locking mechanism to prevent successive operation of one door without intervening operation of the other.

5. In combination, a compartment, a plurality of doors associated therewith, locking means for one of said doors, an interlocking connection preventing release of said locking means until after actuation of the other door, and connections operated by opening and 60 closing said first mentioned door for adjust-

ing said interlocking connection and locking said door.

6. In combination, a compartment, a plurality of doors associated therewith, means automatically operated by moving either door to closed position for holding said door closed, and interlocking means also operated automatically by closing one of said doors to prevent release of said door until another door has been opened and closed. 70

7. In combination, an enclosure, doors in said enclosure, and interconnections for preventing opening of one door after it has been closed until after actuation of the opposite door, said interconnections including duplicate elements projecting inwardly from each door and having locking irregularities of contour, means engaged by the element on one door upon closing to retain said door closed, and means operated by the other element for readjusting said interconnections to permit subsequent release of said first element. 75

8. In combination, an enclosure, doors in said enclosure, and interconnections for preventing opening of one door after it has been closed until after actuation of the opposite door, said interconnections including elements projecting inwardly from each door and having locking irregularities of contour, means engaged by the element on one door upon closing to retain said door closed, and means operated by the other element for readjusting said interconnections to permit 80 subsequent release of said first element. 90

9. In combination, an enclosure, doors in said enclosure, a locking element carried by one door, locking means operated automatically by moving said door to closed position for preventing subsequent opening thereof, a similar element carried by the other door, and means actuated by said last mentioned element for readjusting said locking means to permit opening of said first mentioned door. 100

10. In combination, an enclosure, doors in said enclosure, a locking element carried by one door, locking means automatically operated by moving said door to closed position, releasing means for said locking means 115 a slideable interlock, connections including said locking element for sliding said interlock in opposite directions upon actuation of said doors, said interlock remaining independently in either shifted position, said interlock co-operating with said releasing means in one position for preventing and in the other position for permitting withdrawal of said locking element. 120

11. In combination, an enclosure, doors 125 on different sides of said enclosure, an interlock extending thru said enclosure, said interlock being slideable to and fro by operation of said doors, and connections between said interlock and one door for locking said 130

door when opened and again closed until after operation of the other door.

12. In combination, an enclosure, doors on different sides of said enclosure, a plate extending thru said enclosure, said plate being slidable to and fro by operation of said doors, locking means for one of said doors automatically holding its door shut when

said door is opened and again closed, said plate having a projection co-operating with ¹⁰ said locking means to release the same upon actuation of the other door.

In witness whereof, I hereunto subscribe my name this 16th day of May 1921.

HARRISON A. SMITH.
